UNITED STATES PATENT OFFICE.

AARON S. NICHOLS, OF CHICAGO, ILLINOIS.

POWER GLUE-SPREADING MACHINE.

SPECIFICATION forming part of Letters Patent No. 673,410, dated May 7, 1901.

Application filed October 22, 1900. Serial No. 34,001. (No model.)

To all whom it may concern:

Be it known that I, AARON S. NICHOLS, a citizen of the United States, residing in Chicago, in the county of Cook and State of Illinois, 5 have invented a new and useful Improvement in Power Glue-Spreading Machines, of which the following is a specification.

This invention relates to the construction of machines for spreading glue on the surfaces of boards which are to be glued to other boards or stock.

The object of the invention is to provide a construction whereby it is rendered wholly unnecessary that the spreading-rolls, or either 15 of them, be internally heated.

In my improved machine I employ a power-driven roll below the path of the stock to be glued, a tank of glue in which this roll revolves, and an upper roll driven from the 20 lower roll and adapted to come in contact with the lower roll, so as to be charged with glue thereby when no stock is passing, and a steam or water heated outer hood placed over the upper roll and inclosing it as nearly as 25 may be, so that the glue upon it does not become chilled or thickened prior to its contact with the stock operated upon. The upper roll is supported in sliding bearings and is free to rise to any extent rendered necessary 30 by the thickness of the stock, and it is also readily removable when the stock is to be glued upon one side only, and the hood is also readily removable to permit the taking out of the upper roll.

35 The nature of my improvements is fully described in the description given below and illustrated in the accompanying drawings, in which—

Figure 1 is a side elevation, partly in section, of the machine. Figs. 2 and 3 are sections on the lines 2 2 and 3 3, respectively, of Fig. 1.

In said drawings, A represents a tank for the liquid glue, supported upon suitable frame-work B. At opposite sides of the tank are upright standards C, in which the gluing-rollers are journaled. The lower roll D is mounted upon the shaft E, and this shaft is driven in any suitable manner by pulleys or 50 otherwise. The power means for driving the

roll is not shown. The roll may be immovably supported in the standards C. The upper roll is shown at F and is carried by the shaft G, the bearings of which are supported in slots H, formed in the top of the standards 55 C. The rolls E and F are permitted to come together when no stock is passing between them, so as to permit the charging of the upper roll with glue by the lower roll, and the upper roll is free to move upward to the extent necessitated by the thickness of the stock, and in practice it is lifted with each piece of stock which is passed through and falls between times, so as to be charged by the lower roll. The shaft E carries a gear J, and the 60 shaft G carries a like gear K. These gears intermesh, so as to secure the driving of the upper roll; but their teeth are cut deep, so that the various changes in position by the upper roll while operating will not destroy the 65 mesh.

Instead of heating the upper roll internally, as has been the custom heretofore, I place over it a steam or water heated hood, which will act to keep the roll sufficiently warm to 75 prevent the glue on it from chilling or thickening. This hood is made with double walls, except at the ends, thereby forming an inclosed steam or water space L, and the heating agent is admitted to this space L by the 80 supply-pipe M, and the water of condensation is drawn off by the pipe N. In the preferred construction of the hood I take channel-irons O, bend them into semicircular form, and apply an outer covering P, an inner covering Q, (both bent to conform to the channel-iron,) and ends R, which are simply cut into form. At both sides the space L is closed at the bottom, as will be understood. The hood is adapted to be thrown back out of operating position, as indicated in dotted lines in Fig. 1, and to permit this without disturbance of the steam or water connections I insert in each of these connections a swing-joint T, preferably the joint described in 95 Letters Patent of the United States No. 652,789, of July 3, 1900, to Adolph Leitelt, Jr. The hood is supported upon its pipe connections by means of the lateral arms C', extending from the standards C, and its move- 100

ments are limited by one or more stops S, attached to the arm C', as seen at Fig. 1.

I claim—

In a power glue-spreader having one or more rolls for applying the glue, and a heated hood covering the upper roll, said hood being connected to separate pipes for the admission and discharge of the heating agent by swing-

joints located at one side of the hood, whereby the hood is adapted to be swung away from its acting position at will, substantially as specified.

AARON S. NICHOLS.
